UNITED STATES PATENT OFFICE.

CLARENCE S. STEWARD, OF CHATTANOOGA, TENNESSEE.

ELECTRIC STOVE.

1,087,199.

Specification of Letters Patent. Patented Feb. 17, 1914.

Application filed November 12, 1913. Serial No. 800,628.

To all whom it may concern:

Be it known that I, CLARENCE S. STEWARD, a citizen of the United States, residing at Chattanooga, in the county of Hamilton and State of Tennessee, have invented certain new and useful Improvements in Electric Stoves; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to certain new and useful improvements in electric stoves and it has for its object, among others, the provision of a heating chamber disposed beneath the stove and adapted for utilizing the waste heat from the heating units and which also serves to prevent the upward rush of cold air which would have a tendency to cool the units and render the same less effective.

The invention contemplates the use of either one or more heat units as may be desired. While I have shown a stove of substantially rectangular form and provided with three heat units, it is at once evident that the form and size as well as number of units employed may be varied without departing from my invention.

The invention is clearly illustrated in the accompanying drawings, which, with the numerals of reference marked thereon, form a part of this application and in which:

Figure 1 is a front view. Fig. 2 is a top plan view. Fig. 3 is a central section on line 3—3 of Fig. 2, and Fig. 4 is a transverse section on line 4—4 of Fig. 3.

Reference now being had to the details of the drawings by numeral, 1 designates the stove which is constructed, preferably, of sheet metal and consists of a compartment 2 arranged beneath the heat unit 3. The wires 4, by means of which the current is maintained through the heat units, are extended along the bottom of the chamber, thence upward along the upper portion of the chamber to the point at which connection is had with the unit or units. Separating the wires at the bottom and end of the compartment is a partition wall 5. Doors 6, 6 are hinged at their lower edges to the edge of the false

bottoms and, when turned upward, serve to close the compartment.

The heat units 3 are seated within suitable openings provided in the top of the stove. These units I have shown as of circular form but it will at once be evident that they may be, if desired, rectangular or other form and may vary in size to suit the requirements. A slight space 7 intervenes between the outer edges of each unit and the surrounding edges of the opening within which each is seated, the object of this opening being to prevent the heat from the unit being imparted to the top of the stove.

In the present instance, I have shown the stove provided with that type of unit in which a series of resistance wires is provided within the upper face of a plate or disk of steatite or soapstone, the heat radiating from the resistance wires being permitted to escape through open slots formed in the surface of the unit and being imparted to the plate upon either side of the slots. Suitable supports, such as legs 15, are provided and the current through the heater is controlled by means of a suitable switch 16 of ordinary construction.

The operation and advantages of the invention will, from the foregoing description, be readily understood.

In the use of the stove, there must necessarily be a certain amount of waste heat within the space beneath the heat units. The essential object of the present invention is to retain this heat for heating or warming purposes. The side walls and false bottom of the chamber 6 being imperforate, it will at once be noted that, when the doors of the compartments are closed, the heat will be thus retained within the compartment and that the compartment will serve as a convenient receptacle for foods which it is desired to keep warm or to be slowly cooked. It will also be noted that the compartment disposed beneath the units will serve at all times to prevent the movement of cold air upward which would result in case the space beneath the units was open to the surrounding atmosphere of the room or compartment within which the stove is located.

The construction which I have shown and described as to the form of the stove, the type of unit employed and the number and size of units may be varied without depart-

ing from my invention which contemplates the use of a closed chamber disposed beneath the electric heating units of an electric cooker, the said chamber serving as a heat retainer for the heat radiating from the lower portion of the heat units.

Having thus described my invention, what I claim to be new and desire to secure by Letters Patent is:—

- 10 1. In an electric cooker of the character described, the combination of the top plate of the stove of one or more electric heating units, said units being seated within openings provided in the top plate of the stove, an imperforate compartment disposed beneath the heaters, and hinged doors communicating with the compartment, substantially as shown and described.

2. In an electric cooking stove, the combination with the top plate of the stove, of a heating unit seated within an opening formed in the top of the stove, an insulating space intervening between the heating unit and the edges of the opening within which it is seated, an imperforate compartment disposed beneath the heat unit, a door to the compartment, and an electric connection with the unit, substantially as shown and described.

In testimony whereof I hereunto affix my signature in presence of two witnesses.

CLARENCE S. STEWARD.
